BOBBIN CLEANER

Julius Edwin Kimbirl, Charlotte, N. C., assignor
to The Terrell Machine Company, Charlotte,
N. C., a corporation

Application October 31, 1934, Serial No. 750,912

6 Claims. (Cl. 28—19)

The invention has relation to machines of the class used in the textile industry for the purpose of stripping so-called feeler-waste, i. e., residues of weft or filling, from bobbins that have been 5 expelled from the working shuttle of an automatic weft-replenishing loom in the performance of bobbin-changing operations brought about under the control of a so-called weft or filling feeler. More particularly, it relates to bobbin-10 stripping machines of the type having blades or the like by which the residue of weft or filling remaining on an expelled bobbin is removed from the bobbin-barrel by a scraping action taking place lengthwise along the bobbin-barrel. An example 15 of this type of machine to which the present invention is adapted, is illustrated in the patent to Edgar A. Terrell, No. 1,740,128, dated December 17, 1929.

A special object of the present invention is to 20 provide a machine of the type illustrated in the aforesaid patent with a simple mechanism for blowing from the interior or bore of the bobbin any lint that may have collected therein, this air-blasting of the lint out of the interior of the bobbin taking place during the usual stripping 25 operations and without delaying or interfering therewith in the least, as more fully hereinafter set forth.

In the drawing annexed, Fig. 1 is a side elevation of my device, this view including so much of 30 the frame of the regular stripping machine as is needed to illustrate an arrangement of parts on the machine;

Fig. 2 is an end elevation of the same. 35 Referring to this drawing by reference characters, 5 designates the usual pusher in bobbin stripping machines of the type referred to. This pusher is ordinarily provided with a bobbin-tip seat which is adapted to receive the tip end of the bobbin and to push it endwise through the 40 scraping knives. In the present instance, I substitute an air nozzle 6 which is fastened to the upper side of the pusher and is provided at its forward end with a tip-seat 7 into which is directed an air-jet 8 so positioned that when the bobbin tip rests in said seat 7 its exit end will be aligned with the bore of the bobbin. An air-pipe 9 is connected to the inlet end of the nozzle jet 8 and at a suitable point in its length it is provided with a flexible section 10, made of air-hose 45 or other flexible tubing.

At a point in the length of the pipe 9, between the flexible section 10 and the inlet end 11 (which inlet is of course connected with a source 50 of compressed air, not shown) there is inserted in

the pipe an air-valve 12, the valve-disk of which is provided with a stem 13 which extends out through a stuffing box in the valve casing. Affixed to the pipe 9 at a point between the flexible section and the nozzle is a horizontal rod 14 5 which is adapted to slide back and forth through a guide-hole in a bracket 15 mounted at a suitable place on the frame of the stripping machine, this bracket serving also as a means of support for the pipe 9 at a point beyond the flexible section thereof. The rod 14 is provided with a tappet 16 whose actuating face or lug lies in the horizontal path of the valve-stem 13, this tappet being adjustable along the length of the rod to enable the appliance to be adapted for bobbins 15 of different lengths.

When the bobbin has gravitated to cleaning position, with its tip resting in seat 7, the pusher 5 is pushed toward the usual stripping blades to thus strip from the bobbin the usual feeler-waste. 20 At a suitable point in the endwise movement of the bobbin, preferably after the usual gripper jaws have grasped the larger end of the bobbin for the purpose of pulling it far enough to complete the stripping action, the tappet 16 contacts 25 with the stem 13 and thus opens the air-valve. The air-blast travels through the pipe 9 and causes a jet to issue out of the nozzle jet 8 and thence throughout the length of the bore of the bobbin, thereby effectively clearing out any lint 30 that may have collected in the bore. After this interior cleaning of the bobbin has been accomplished, the pusher 5 is moved rearwardly to its bobbin-receiving position, thus allowing the air-valve to close and putting the appliance in 35 condition for another operation upon the succeeding bobbin. The insertion of a flexible section 10 in the air-pipe 9 enables the operations above described to take place without the use of telescopic pipe sections or other undesirable 40 devices.

I claim:

1. In combination with a bobbin-stripping machine having as an element a bobbin-pusher to shift a bobbin endwise for stripping it, an air-nozzle mounted on said pusher and provided with a tip-seat for a bobbin, said air-nozzle being movable back and forth with said pusher in the usual stripping operations, and means for supplying a blast of air to said nozzle actuated by the movement of said pusher to deliver a blast of air to the nozzle at the forward end of the stroke of the pusher, said means embodying an air-supply pipe connected to the nozzle and having a flexible section, a valve in said pipe at a point between 50

said flexible section and the inlet end of the pipe, and a valve-actuating appliance attached to the pipe at a point between said flexible section and the nozzle and provided with means for opening 5 said valve when the pusher has reached approximately the end of its bobbin-shifting stroke.

2. The structure recited in claim 1, said means embodying an air-blast pipe having its outlet end connected to said nozzle and having a flexible 10 section in its length, a bracket fastened to the frame of the machine and attached to that section of the pipe between its inlet end and the flexible section, a valve-rod attached to that section of the pipe between the flexible section and 15 the nozzle and having a sliding support on said bracket, a valve in said pipe at the point where it is fastened to said bracket, and a tappet on said valve-rod arranged to actuate said valve to open position when the pusher with its nozzle has 20 reached approximately the end of its pushing stroke.

3. Bobbin-cleaning apparatus comprising a reciprocable bobbin pusher to shift a bobbin endwise for stripping it and having an air discharge 25 port and a seat for an end of a bobbin both borne by the pusher to reciprocate therewith, said seat being correlated with said port for support of said bobbin end with the central bore of the bobbin in endwise register with the air discharge 30 port as the pusher shifts the bobbin on its stripping movement, and means for supplying a blast of air to the discharge port actuated by the bobbin-shifting movement of the pusher to deliver a blast of air to said discharge port to blow out 35 the bore of the bobbin when the bobbin has been advanced in its stripping movement.

4. Bobbin-cleaning apparatus comprising a reciprocable bobbin pusher to shift a bobbin endwise for stripping it and having an air discharge 40 port and a seat for the end of a bobbin both borne by the pusher to reciprocate therewith, said seat being correlated with said port for sup-

port of said bobbin end with the central bore of the bobbin in endwise register with the air discharge port as the pusher shifts the bobbin on its stripping movement, an air supply conduit in delivery connection with said discharge port 5 and having valve means to control flow of air through the conduit to said port, and means actuated by the bobbin-shifting movement of the pusher to operate said valve means to admit a blast of air from the conduit to the discharge 10 port to blow out the bore of the bobbin when the bobbin has been advanced in its stripping movement.

5. Bobbin-cleaning apparatus according to claim 4, characterized in that the said valve 15 means is mounted in a fixed position, the air supply conduit has a flexible section between the valve means and the said air discharge port, and a valve-operating device is operatively connected to the bobbin pusher for reciprocation therewith 20 to operate the valve means for flow of air through the conduit to the discharge port to blow out the bore of the bobbin when the bobbin has been advanced in its stripping movement.

6. Bobbin-cleaning apparatus comprising a 25 bobbin mover shiftable to move a bobbin endwise for stripping it and having an air discharge port and bobbin-supporting means both borne by the bobbin mover to shift therewith, said bobbin-supporting means being correlated with 30 said port for support of an end of a bobbin in a position with the central bore of the bobbin in endwise register with the port as the bobbin mover shifts the bobbin on a stripping movement, and means for supplying a blast of air to 35 the discharge port actuated by the bobbin-shifting movement of the bobbin mover to deliver a blast of air to said discharge port to blow out the bore of the bobbin when the bobbin has been advanced in its stripping movement. 40

JULIUS EDWIN KIMBIRL.
